START STOP UNLOADER FOR MULTIPLE STAGE COMPRESSORS

Filed April 19, 1932

UNITED STATES PATENT OFFICE

JOHN LE VALLEY, OF PAINTED POST, NEW YORK, ASSIGNOR TO INGERSOLL-RAND COMPANY, OF JERSEY CITY, NEW JERSEY, A CORPORATION OF NEW JERSEY

START STOP UNLOADER FOR MULTIPLE STAGE COMPRESSORS

Application filed April 19, 1932. Serial No. 606,109.

This invention relates to compressors, but more particularly to an unloader for compressors.

5 One object of the invention is to reduce the load on the prime motor of the compressor during the starting period of the compressor.

Another object is to produce an inexpensive and simple unloader which may be 10 cheaply maintained and which will be positive in operation.

Other objects will be in part obvious and in part pointed out hereinafter.

In the drawing accompanying the specification and in which similar reference characters refer to similar parts,

Fig. 1 is a section through a compressor of a type adapted to be fitted with an unloader as contemplated by the invention, and

20 Fig. 2 is a longitudinal section through the cylinder of the compressor and the unloading means constructed in accordance with the practice of the invention together with associated parts of the compressor mechanism also shown in section.

25 Referring to the drawing and more particularly to Fig. 1 the compressor includes a base 10 upon which are suitably mounted a low pressure cylinder 12 and a high pressure cylinder 14 provided with pistons 16 and 18 respectively. The piston 16 is adapted to be reciprocated by a connecting rod 20 mounted on the crank pin 22 of the crank shaft 24. Likewise the piston 18 is provided with a connecting rod 26 journalled 30 on the crank pin 22. The low pressure cylinder 12 is provided with a suitable inlet valve 28 and a discharge valve 30 controlling the flow of compressed fluid to a manifold 32. Suitable cooling conduits 34 connect the manifold 32 to an inlet manifold 36 suitably attached to the high pressure cylinder 14 which is provided with suitable inlet and discharge valves 38 and 40 respectively.

45 The compressor above described is quite similar to that disclosed in my co-pending application No. 510,140 filed January 21, 1931 and as in the case of that compressor, it is highly desirable that the load be removed 50 during the starting period of the compressor

and particularly would be driven by a motor having relatively low starting torque.

The invention herein to be described is an improvement over the unloader described in the above mentioned application in that it provides a means for utilizing a relatively small centrifugal mechanism for unloading the high pressure cylinder 14 when the compressor is operated at relatively high discharge pressures. To this end the unloader is provided with relief devices which are adapted to be operated by fluid pressure below that of the discharge of the high pressure cylinder. In this instance the pressure utilized is that which obtains in the intercooler conduits 34. The unloading mechanism includes a plug 42 fitted into an aperture 44 of the high pressure cylinder 14 terminating in a passageway 46 leading to the interior of the cylinder 14. The plug 42 is hollow, being provided with two concentric bores 48 and 50, the former bore being of larger diameter than the latter and both bores being connected by a valve seat 52 upon which a ball 55 check valve 54 is adapted to rest, being resiliently held in this position by means of a spring 56. An aperture 58 in the plug 42 is adapted to receive a threaded tube 60 which leads to a pilot valve 62. The pilot valve 62 60 consists of a body 64 having opposed apertures 66 and 68 connected by a bore 70 into which is slidably fitted a plunger rod 72. The aperture 68 is closed by means of a valve seat plug 73 provided with a valve seat 74 65 for a ball valve 76 which is adapted to be pressed onto the seat 74 by means of the plunger rod 72. The plug 73 is provided with a threaded aperture 78 to receive the threaded tube 60 which communicates with 70 a bore 80 to receive a valve spring 82 normally tending to maintain the ball valve 76 off its seat.

The aperture 68 is closed by a diaphragm 84 held in place by a suitable cap 86 threaded 85 onto the end of the valve body 64 as at 88. The diaphragm 84 is arranged to actuate the plunger rod 72 through the medium of the plunger head 90 integrally formed with the rod and bearing against the diaphragm 84 100 due to the pressure of the spring 82.

The interior of the cap 86 and the dia-
phragm 84 form a chamber 92 into which
pressure fluid is admitted by means of a pipe
94 connected by means of a pipe 96 to the dis-
charge manifold 32 of the low pressure cyl-
inder 12. The chamber or aperture 66 is
maintained at atmospheric pressure by means
of a vent 98 and vent pipe 100 leading to
atmosphere. Similarly the chamber 68 is
10 maintained at atmospheric pressure by a
suitable vent 102 also leading to atmosphere.

The pipe 96 is also adapted to act as a vent
for unloading the low pressure cylinder by
reducing the pressure in the discharge mani-
fold 32 to atmosphere and to this end a
15 branch pipe 104 is provided connecting with
the pipe 96 at a T 106. The venting of pipe
104 is controlled by a ball valve 108 con-
tained in a plug 110 to which the pipe 104 is
20 connected. The plug 110 is provided with a
large concentric bore 112 and a smaller bore
114 joined by a conical valve seat 116 for the
ball valve 108. Normally the ball valve 108
is held upon its seat 116 by means of a spring
25 118 within the bore 112. When the com-
pressor is at rest or when operating at slow
speed the ball valve 108 is centrifugally op-
erated by a plunger rod 120, having a reduced
30 end 122 adapted to pass through the small
bore 114 of the plug 110. Preferably the
plug 110 is fitted into a portion 124 forming
part of the compressor base 10 and its bore
114 is coaxial with the crank shaft 24. In
35 order that the rod 120 may hold the ball valve
108 off its seat when the compressor is not
running, a cup-shaped end 126 is provided
within which a spring 128 is inserted nor-
mally tending to push the rod 120 in the
40 direction of the ball valve.

40 Centrifugal means are provided to depress
the spring 128 and withdraw the rod 120
when the compressor has reached a predeter-
mined speed of operation. To this end the
45 shaft 24 is provided with a cylindrical ex-
tension 130 bolted to the shaft at flanges 132
by means of bolts 134 and is adapted to re-
ceive the cup-shaped end 126 of the rod 120.

45 A pair of arms 136 weighted as at 138 are
pivotally mounted as at 140 upon lugs 142
50 integrally formed with the cylindrical exten-
sion 130 and are provided with ends 144 bear-
ing against the cup-shaped end 126 of the
rod 120. Upon rotation of the shaft 24 the
55 weighted ends 138 of the arms are adapted to
overcome the tension in the spring 128 and
to depress the cup-shaped member 126 there-
by withdrawing the rod 120 and releasing
the ball valve 108.

60 In order to permit the escape of air or
gas under pressure the rod 120 is provided
with flat sides as at 146 and additionally the
aperture 148 in the portion 124 of the base is
of slightly larger diameter than the rod 120.

65 In the operation of the device, while the
compressor is not running the spring 128

forces the rod 120 to unseat the ball valve 108
thereby permitting the escape of any gas
under pressure which may exist in the mani-
fold 32 or the intercooler tubes 34 by way of
the tubes 96 and 104. In this position also
70 the spring 82 forces the ball valve 76 from
its seat 74 thereby permitting the escape of
any fluid compressed in the high pressure
cylinder 14 by way of the plug 42 and the
75 pipe 60, the bore 80 and bore 98 of the pilot
valve and thence by way of the pipe 100 to
any suitable receptacle or to atmosphere.

Upon speeding up of the compressor centrif-
ugal force acting upon the weights 138 causes
the ends 144 of the arms 136 to depress the
80 plunger rod 120 thereby releasing the ball
valve 108 which is forced to unseat by the
spring 118.

85 Since the air being compressed in the low
pressure cylinder 12 and discharged into the
manifold 32 can no longer escape pressure
will then build up in the chamber 92 of the
pilot valve until the pressure upon the dia-
phragm 84 is sufficient to overcome the pres-
90 sure of the spring 82 and the pressure of the
air being discharged through the bore 80 of
the pilot valve. The plunger rod 70 is there-
upon moved by the pressure from the dia-
phragm 84 to force the ball valve 76 to its
95 seat 74 holding it tightly thereagainst.

Being closed to the escape of gas under
pressure the volume within the pipe 60 will
act as a clearance for the cylinder 10 until
completely filled with gas under the maxi-
100 mum pressure obtainable in the cylinder 14
whereupon the check valve 54 remains upon
its seat 52 due to the biasing tension of the
coil spring 56.

105 It will be seen therefore that during the
starting period of the compressor the cylin-
ders are unloaded until the speed is such that
the centrifugal force of the weight 138 is
sufficient to overcome the tension of the
110 spring 128 and that the high and low pres-
sure cylinders load successively, the low pres-
sure cylinder being loaded first and arranged
to control the loading of the high pressure
cylinder. It will be seen that the low pres-
sure cylinder will load slowly due to the fact
115 that the intercooler tubes 34 and the mani-
folds 32 and 36 have considerable storage
capacity. The high pressure cylinder is
loaded only upon the building up of the pres-
sure in the manifold 32 and the load is thrown
120 onto the high pressure cylinder 14 relatively
slowly due to the relatively slow closing of
the ball valve 76.

125 Thus by the above construction are accom-
plished, among others, the objects herein-
before referred to.

I claim:

1. A start stop unloader for multiple stage
compressors comprising means to control the
escape of the discharge of one stage to atmos-
phere for unloading and loading that stage
130

of the compressor upon stopping and starting respectively of the compressor, and means operable by said loading means for loading another stage of said compressor.

- 5 2. A start stop unloader for multiple stage compressors comprising means associated with the discharge of one stage of said compressor to permit the escape of fluid therefrom upon stopping of the compressor, means
10 for unloading the second stage of said compressor, and means controlled by the discharge pressure of the first stage to control said unloading means for the other stage.
- 15 3. A start stop unloader for multiple stage compressors comprising a centrifugally operated means for reducing the discharge pressure of one stage of the compressor when the compressor comes to rest, and fluid operated means for controlling another stage
20 of the compressor operated by the discharge pressure of the first said stage.
- 25 4. A start stop unloader for a compressor having a pair of compression chambers and a discharge chamber for one of said chambers leading to the inlet of the second compression chamber, a centrifugally operated escape valve to reduce the pressure in said discharge chamber when the compressor comes to rest, a conduit leading from one of
30 said compression chambers to atmosphere, and a valve controlled by the pressure in the said discharge chamber for controlling the escape of fluid from said conduit to atmosphere.
- 35 In testimony whereof I have signed this specification.

JOHN LE VALLEY.
